UNITED STATES PATENT OFFICE.

WILLIAM ERNEST LAYCOCK, OF SHEFFIELD, ENGLAND.

SASH-BALANCE.

1,118,561.

Specification of Letters Patent. Patented Nov. 24, 1914.

Application filed April 10, 1913. Serial No. 760,114.

To all whom it may concern:

Be it known that I, WILLIAM ERNEST LAYCOCK, subject of the King of Great Britain, residing at Sheffield, in the county 5 of York, England, have invented certain new and useful Improvements in Sash-Balances, of which the following is a full, clear, and exact description.

This invention relates to improvements in 10 frameless windows for vehicles. In doors of motor cars and other vehicles it has hitherto been found difficult to apply so called frameless windows in view of the fact that the lazy tongs employed for windows of this class together with the spring 15 for overcoming the weight of the window, require more space than is obtainable at the bottom of the door, which usually, for the sake of appearance, has the front lower 20 corner rounded off. Again as the said door is more or less curved at the lower portion when viewed edgewise on, the rigidity of the counterbalancing gear as a whole does not permit the window to be lowered beyond 25 a certain point as the said gear would foul the back of the front panels of the said door.

The present invention has for its object 30 to provide an improved construction and arrangement of the window and the lazy tongs gear whereby the aforesaid objections may be avoided and to this end it comprises the improvements hereinafter described and pointed out in the claim and 35 by virtue of which the lazy tongs is permitted to adjust itself at a sufficient angle relatively to the window to enable the said window to be lowered or raised to such extent as may be desired.

40 In order that the invention may be the better understood drawings are appended in which:—

Figure 1 is a rear view of a door embodying the present invention the interior panels 45 being removed and the window shown open. Fig. 2 is a similar view with the window closed. Fig. 3 is a vertical section on line A A Fig. 2. Figs. 4 and 5 are respectively views showing to an enlarged scale the 50 knuckle joints or connections at the upper and lower ends of the lazy tongs.

Referring to the appended drawings a

indicates generally the door which as shown in Figs. 1 and 2 has the lower corner a^1 rounded off. The door is also as shown in 55 Fig. 3 so far as its vertical sectional outline is concerned curved at its lower portion a^2 . It will however be understood that so far as the illustrations are concerned that both the extent of the rounding off of the 60 corner a^1 and the curvature at a^2 or of the door generally will vary considerably in accordance with the general contour of the exterior surface of the vehicle.

b indicates the metal channel shaped 65 member in which is secured in any desired manner the sheet of glass c . Secured by screws d to the under surface of the member b are brackets d^1 from which project perforated lugs d^2 and through which lugs 70 pass pins e . The pins e also pass through perforations in the ends of the upwardly extending lugs f at each end of the frame g and through which lugs pass the hooks g^1 to which are attached one end of the springs 75 g^2 . The hooks g^1 are screw threaded at their outer end and have upon them nuts g^3 whereby the tension of the springs g^2 may be adjusted. The springs at their 80 opposite ends are attached to the hooked shaped extremities h of the upper end of a system of lazy tongs h^1 and which lazy tongs are connected by means of a knuckle joint indicated generally by i to the upper surface 85 of the lower member a^3 of the door frame. By means of this arrangement as will be 90 readily understood the lazy tongs when the window is lowered may assume a position such that they lie at such an angle to the curved surface of the inner and outer panels of the door that they do not foul said surfaces and the window may be raised or lowered to the desired extent.

It will be understood that although I 95 have described a specific form and construction of joint and arrangement of springs that I do not consider myself limited to such parts and arrangement as any other structure or structures that permit of the lazy tongs adjusting themselves at the desired angle relatively to the plane of glass sheet are within the scope of this invention.

I claim:

The combination of a window, a support-

ing member therefor, lugs at each end of said member, a frame having corresponding lugs, pins passing through the aforesaid pair of lugs, lazy tongs connected at their upper ends to said frame, springs connected to the upper ends of said tongs at one end, members adjustable in the lugs at the end of the frame connected to the other

ends of said springs and knuckle joint at the lower ends of said tongs.

In witness whereof I have subscribed my signature in the presence of two witnesses.

WILLIAM ERNEST LAYCOCK.
